MULTICOLOR SHUTTLE CHANGING LOOM

Richard Greenleaf Turner, Worcester, Mass., assignor to Crompton & Knowles Loom Works, Worcester, Mass., a corporation of Massachusetts

Application September 1, 1931, Serial No. 560,573
Renewed February 10, 1936

13 Claims. (Cl. 139—232)

This invention relates to multicolor shuttle changing looms, and it is the general object of the invention to make provision for effecting rapid and complete exchanging of shuttles.

5 In fancy shuttle-changing looms a magazine is usually employed to furnish shuttles of variously colored wefts, together with a weft detector to initiate transfer. The selected shuttle is usually advanced from its stack or cell to an intermediate 10 position from which it is conveyed to the lay. If a changing operation is started and a shuttle moved to intermediate position, but not completed due to shuttle misplacement or failure of the changer, it is necessary to have some provision for ridding the loom of the unchanged shuttle. If this is not done, breakage may result, or a shuttle of the one color might replace a differently colored shuttle on a later pick of the loom. It is an important object of my invention to provide for expelling an indicated but 15 unchanged shuttle.

In multicolor shuttle changers heretofore proposed there has been a platform common to the different stacks of reserve shuttles on which the shuttle rested momentarily before being moved 20 to the lay. Because of the space required for movement of the platform, the shuttle is dropped a relatively long distance to the lay, in this way lowering the rate at which the loom may be 25 operated. It is an important object of the present invention to eliminate the platform and provide lay carried supports on which the shuttle falls directly when moving from its cell. The tops of the supports are preferably concentric with 30 the lay axis, in order to hold the shuttle in substantially the same horizontal position until it is ready to move into the shuttle box. The resulting quicker transfer of the shuttle permits the loom to be operated at a higher rate of speed.

40 With these and other objects in view which will appear as the description proceeds, my invention resides in the combination and arrangement of parts hereinafter described and set forth in the claims.

45 In the accompanying drawings, wherein a convenient embodiment of my invention is set forth,

Fig. 1 is a front elevation of a shuttle changer mechanism having my invention applied thereto,

Fig. 2 is a top plan view of the lay shown in Fig. 1, looking in the direction of arrow 2—2,

Fig. 3 is a vertical section on line 3—3 of Fig. 1 with the untransferred shuttle being moved forwardly,

Fig. 4 is a view similar to Fig. 3 but showing 50 the manner of ejecting the shuttle from the lay,

the shuttle having been derived from the front cell of the magazine,

Fig. 5 is a view similar to Fig. 3 but showing the manner of moving the lowest shuttle from the rear cell of the magazine toward transfer position,

Fig. 6 is a view similar to Fig. 5 showing the shuttle resting on the lay supports, and

Fig. 7 is an end elevation of the structure shown in Fig. 1, parts being in section and taken in the direction of arrow 7, Fig. 1.

Referring to the drawings, I have shown a loom frame 10 and a lay 11 over one end of which is arranged a multicolor reserve shuttle magazine M. Front, intermediate and rear walls 15 12, 13 and 14, respectively, define front and rear compartments F and R, respectively, in which the shuttles are stored as they await transfer, the cells having shuttles of differing characteristics, such as size or color. The front cell feeding mechanism 15 has a shuttle supporting shelf 16 movable about a shaft 17 which also supports a retainer 18 positioned to engage the next to the bottom shuttle in the front stack. A spring 19 arranged as shown in Fig. 1 acts to move the retainer into 20 shuttle holding position whenever the shelf 16 is moved from under the stack by an upward movement of pull wire 20, shown in Fig. 7.

A plunger head 21 is located normally behind the bottom shuttle of the rear stack R and may be 25 actuated by a bell crank lever 22 pivoted about a center 23 by a pull rod 24. The wires 20 and 24 extend downwardly to mechanism not shown herein designed to exert a downward pull, depending upon which shuttle is active and exhausted, so that one or the other of these wires can be given an operative movement to effect an exchange of shuttles. The rear shuttles rest on a shelf 25 and the plunger head is so arranged as 30 to support the upper shuttles of the rear stack 35 when in operation.

The space in front of the rear shuttle and below the front shuttles and designated herein at C is a transfer compartment common to both stacks. The front of the compartment is defined by a 45 movable wall 30 pivoting about an axis 31 against the action of a twist spring 32. The wall is ordinarily so placed as to engage a shuttle in transfer position to place the same for proper movement toward the lay.

The lay supports a box mechanism B having top and bottom shuttle boxes 33 and 34, respectively, which slide along a plate 35 provided with a picker slot 36. A binder 37 pivoted to the lay 50 independently of the boxes has upwardly and for- 55

wardly bent horns 38. The bottom 39 for the top box 33 together with the binder and the wall 35 cooperate with a cover 40 hinged to the mechanism B at 41 to define the top box. The cover 5 has a roller 42 to engage a cam 43 fixed to the magazine. A box lifter rod 44 is attached to the boxes and acts to raise the same when a shuttle change is to occur, being called into action by the weft detector, not shown, in known manner.

10 The mechanism thus far described of itself forms no part of my present invention and may be similar to the structure set forth in my co-pending application Serial No. 460,746.

In carrying my improvements into effect I secure to the lay a pair of rearwardly extending supporting fingers 50. These fingers as shown in Figs. 2, 3 and 4 project rearwardly from the boxes and are secured as shown herein to the upper part of the box back 35. They may if desired be made 20 as a part of the box back and preferably have upper surfaces 51 which are concentric with the center around which the lay swings. The fingers or supports lie very close to the plate 25 and extend above the top of the cover 40 when the latter is down. So far as this last provision is concerned, however, it is sufficient if there is some part of the lay behind the boxes which extends above the cover 40 for a purpose to be set forth hereinafter. The supports 50 extend rearwardly 30 a sufficient distance to have supporting relation with a shuttle delivered from the compartment C when the lay is in a forward position, such as that set forth in Fig. 4.

In operation, a shuttle drawn from either of the stacks F or R may be moved into the transfer compartment C, preferably at the time the lay is in its forward position. The shuttle will immediately fall on the supports 50, being thus supported by the lay. Mechanism not shown herein 40 but set forth in the application mentioned hereinbefore will act to raise the box mechanism until the roll 42 is in engaging position with the cam 43. Subsequent rearward movement of the lay will lift the cover 40 so that the shuttle on the 45 supports, which is held against rearward movement by the front of the plate 25, will pass under the cover. Eventually the lay will reach its rear-most position to place the box back 35 either in line with or slightly behind the front of the plate 25, whereupon the shuttle will fall into the top box 33. The subsequent forward movement of the lay will pull the roll 42 away from the cam 43 and the cover will return to its normal down or horizontal position, the effect of which is to 55 seat the shuttle on the partition or floor 39.

Because of the action of the fingers 50 in supporting the shuttle I am enabled to lower the magazine so that the vertical travel of the shuttle from the compartment C into the box 33 is 60 relatively short. By allowing the incoming shuttle to fall directly upon a part carried by the lay I eliminate intermediate supports, which in prior constructions have lengthened the path of travel of the shuttle and have therefore lowered the 65 operating speed of the loom. I find that the fingers set forth herein permit a high speed with more precise movements on the part of the incoming shuttle. It is to be understood that when the normal transfer has resulted in placing a 70 fresh shuttle in the top box 33, the boxes will move downwardly to position the shuttle for picking.

If for any reason the box mechanism should not rise to take the shuttle on the fingers 50, it 75 is desirable to eject the shuttle from the lay.

Under these conditions, which may result from misindication of the lifting mechanism for the boxes, the latter will be down while the incoming shuttle is on the fingers 50, and as the lay moves rearwardly the fingers will move out of supporting relation with the shuttle, and the latter will fall along the box back and onto the cover 40, assuming the position shown at E in Fig. 3. As the lay advances the box back 35 will move the shuttle forwardly against the retainer 10 30. The latter is capable under these conditions of swinging forwardly and upwardly far enough to allow the shuttle to pass thereunder and slide over the cover, passing through a position shown at E' in Fig. 4, toward a spent shuttle receiver 55. 15

By referring to the last named figure it will be seen that the dot and dash line 60 which indicates the path of movement of the lowest part of the retainer will rise above the top of the shuttle when the latter is in the dot and dash line 20 position shown at 61. The untransferred shuttle therefore passes out of control of the retainer before the lay reaches front center. The momentum of the shuttle derived from the lay is sufficient to throw the shuttle forwardly into the container 55 as the lay comes to rest momentarily at front center.

It is to be understood that the ejection of the shuttle as set forth in the form of the invention shown herein depends upon movement of the incoming shuttle into a position where it can be controlled by the lay even though the box mechanism B fails to rise. In previous constructions the incoming shuttle has rested on an intermediate platform or the like which depended for its actuation upon the raising of the boxes, so that if the latter failed to rise the shuttle remained on the platform and there was no way of moving it out of the magazine. As a result of these prior constructions it was not possible in multicolor work to prevent a confusion of colors, but by the mechanism shown herein any shuttle which is started on the transferring movement toward the lay is certain either to be correctly transferred, or will be ejected to prevent confusion of colors. 45

From the foregoing it will be seen that I have provided means in a shuttle changer which insures one of two actions on the part of a shuttle which starts a transfer motion, either it has a normal transfer, or is ejected from the operating parts of the loom. The normal transfer is allowed to be more rapid by reason of the fact that the shuttle falls on the fingers 50, and the ejection of an indicated shuttle is rendered possible by placing it under control of the lay, this result also being accomplished by letting it fall on the fingers to move with the lay. It will also be seen that a shuttle which starts from the magazine toward picking position will be ejected if for any reason it fails to reach such position or if it fails to be boxed. By making the surfaces of the fingers or arms on the lay concentric with the lay axis the shuttle may be kept in the same relative position with respect to the magazine and lay as the latter swings. 55

Having thus described my invention it will be seen that changes and modifications may be made therein by those skilled in the art without departing from the spirit and scope of the invention and I do not wish to be limited to the details herein disclosed, but what I claim is:

1. In a multicolor shuttle changing loom operating with a plurality of callable shuttles having diverse weft and any one of which may become active, a group of reserve shuttles for each calla- 75

ble shuttle, means operative upon substantial exhaustion of weft in any active callable shuttle to initiate replacement of said exhausted shuttle by a shuttle drawn from the corresponding group, 5 and mechanism operative during continued running of the loom to eject from the loom the shuttle drawn from the group should said drawn shuttle fail to replace the exhausted shuttle, to the end that confusion of colors will be avoided should 10 another callable shuttle become active.

2. In a multicolor shuttle changing loom, a lay movable regularly back and forth therein, a plurality of diverse groups of reserve shuttles above the lay, a box on the lay to receive a reserve shuttle, the front group to be directly over the box and another group behind the box when the lay is in rearmost position, support means on the lay extending rearwardly from the box to lie under the front group when the lay is in a forward position and behind the front but under the other group when the lay is in rearmost position, means effective to deposit a reserve shuttle from any group on the support means when the lay is in a forward position, the support means moving from under a shuttle thereon as the lay moves to rear position and the shuttle thereupon moving into the box. 25

3. In a multicolor shuttle changing loom, a lay movable back and forth therein, a plurality of diverse groups of reserve shuttles above the lay, a box on the lay to receive a reserve shuttle, the front group to be directly over the box and another group behind the box when the lay is in rearmost position, support means on the lay extending rearwardly from the box to lie under the front group when the lay is in a forward position and behind the front but under the other group when the lay is in rearmost position, means effective to deposit a reserve shuttle from any group 30 on the support means when the lay is in a forward position, the support means moving from under a shuttle thereon as the lay moves to rear position and the shuttle thereupon moving down in front of the support to be moved forwardly positively by 40 the lay.

4. In a shuttle changing loom, a magazine of reserve shuttles, a regularly moving lay, a receptacle on the lay to receive a shuttle from the magazine, means to release a shuttle from the magazine, and a support on the lay to hold the released shuttle until the receptacle moves under the shuttle, whereupon the latter will move into the receptacle. 50

5. In a multicolor shuttle changing loom, a magazine having a plurality of groups of diverse shuttles, a lay movable regularly under the magazine, a receptacle on the lay to receive a shuttle from the magazine, means to release a shuttle from any group, and support means on the lay to receive a shuttle released shuttle and hold the same until the receptacle moves into position to receive the shuttle. 60

6. In a multicolor shuttle changing loom, a magazine having a plurality of groups of diverse shuttles, a lay movable regularly under the magazine, means defining a magazine compartment common to the groups to receive a shuttle drawn from either group, a receptacle on the lay movable under the compartment to receive a shuttle in said compartment to receive a shuttle in said compartment, and means positioned during part of the movement of the lay to form part of the compartment and hold a shuttle in said compartment until the receptacle moves under 75 said compartment.

7. In a multicolor shuttle changing loom, a magazine having a plurality of groups of diverse shuttles, a lay movable regularly under the magazine, means defining a magazine compartment common to the groups to receive a shuttle drawn from either group, a receptacle on the lay movable under the compartment to receive a shuttle in said compartment, and means carried by and moving with the lay and positioned during part of the movement of the lay to form part of the 10 compartment and hold a shuttle in said compartment until the receptacle moves under said compartment. 5

8. In a shuttle changing loom, a magazine of reserve shuttles, a regularly moving lay, a receptacle on the lay to receive a shuttle from the magazine, means to release a shuttle from the magazine, and a support on the lay having a surface concentric with the axis of the lay to hold the released shuttle until the receptacle moves 20 under the shuttle, whereupon the latter will move into the receptacle. 15

9. In a shuttle changing loom, a lay movable backwardly and forwardly in a horizontal direction, shuttle box mechanism on the lay movable vertically relatively to the lay, a magazine having a supply of reserve shuttles, a cover for the box mechanism which in normal position has a substantially horizontal smooth upper surface, means to raise the cover at the time of shuttle change to clear the path of a shuttle moving from the magazine into the shuttle box mechanism, and means carried by the lay to impart a forward motion to a shuttle derived from a magazine and resting on top of the cover should the latter fail to be raised during shuttle change operation to eject the unchanged shuttle over the cover and away from the lay when the lay moves forwardly. 25

10. In a shuttle changing loom, a lay movable backwardly and forwardly in a horizontal direction, movable shuttle box mechanism on the lay, a magazine having a supply of reserve shuttles, a cover for the box mechanism which in normal position has a substantially horizontal smooth 30 upper surface, means to raise the cover at the time of shuttle change to clear the path of a shuttle moving from the magazine into the shuttle box mechanism, and means carried by the lay to impart a forward motion to a shuttle derived from a magazine and resting on top of the cover should the latter fail to be raised during shuttle change operation to eject the unchanged shuttle over the cover and away from the lay when the lay moves forwardly. 35

11. In a shuttle changing loom, a lay movable backwardly and forwardly in a horizontal direction and having a surface with a vertical component, shuttle box mechanism, a cover for the box mechanism having a top surface having a horizontal component, said surface of the cover lying below part of the surface having the vertical component on the lay, a reserve shuttle magazine, and means to raise the cover to provide a clear path for a reserve shuttle moving from the magazine into the shuttle box, a shuttle derived from the magazine resting on top of the cover when the latter fails to move to clear the path of the shuttle, said shuttle on the cover being 40

acted upon by the lay surface having the vertical component to move said unchanged shuttle off the cover by horizontal motion derived from the lay. 60

12. In a multi-shuttle shuttle changing loom, a lay movable back and forth therein, a maga- 70

- zine having a plurality of stacks of reserve shuttles above the lay, a receptacle on the lay to receive a shuttle drawn from any of the reserve stacks, support fingers on the lay extending rearwardly therefrom, the front stack of the magazine aligning substantially vertically with the receptacle when the lay is in rear position, a shelf for a stack back of the front stack to support a reserve shuttle of said back stack, said fingers 10 extending rearwardly to the shelf when the lay is in forward position, and means to move a reserve shuttle from said back stack from the shelf onto the fingers and effective to place such shuttle over the receptacle on the lay.
- 15 13. In a multi-shuttle shuttle changing loom, a lay movable back and forth in the loom, a

shuttle receiving receptacle on the lay, a reserve shuttle magazine having front and rear stacks for reserve shuttles, the bottom of the front stack being substantially vertically aligned with the receptacle on the lay when the latter is in rearmost position, a shelf under the rear stack to support a shuttle of said rear stack, fingers on the lay extending rearwardly to be under the front stack at all times and extend to the shelf when the lay is in forward position, and means 10 to move a reserve shuttle from the rear stack along the shelf and onto the fingers to a position over the receptacle on the lay when the latter is in rear position.

15

RICHARD GREENLEAF TURNER.
